UNITED STATES PATENT OFFICE.

RANDOLPH CROMPTON, OF CHATHAM, MASSACHUSETTS.

STOPPING INSTRUMENTALITY AND MECHANISM FOR TEXTILE APPARATUS.

1,142,752.

Specification of Letters Patent.

Patented June 8, 1915.

Application filed October 20, 1913. Serial No. 796,157.

To all whom it may concern:

Be it known that I, RANDOLPH CROMPTON, a citizen of the United States, and a resident of Chatham, in the county of Barnstable and

5 State of Massachusetts, have invented an Improvement in Stopping Instrumentalities and Mechanisms for Textile Apparatus, of which the following description, in connection with the accompanying drawings, is a 10 specification, like characters on the drawings representing like parts.

This invention relates to stopping instrumentalities and mechanisms for textile apparatus, and particularly for looms.

15 In order that the principle of the invention may be readily understood, I have disclosed a single embodiment thereof in the accompanying drawings, wherein—

Figure 1 is a front elevation of a portion 20 of two heddle frames each having my improved heddle device mounted thereon; Fig. 2 is a vertical transverse section, showing the heddle devices in side elevation, the shed being closed; Fig. 3 is a view similar to Fig. 25 2, the shed being open; Fig. 4 is a view similar to Fig. 3 but indicating warp fault and the consequent movement of a heddle device. Fig. 5 is a view, with parts broken away or omitted, but generally similar to Fig. 2, and 30 representing a modified form of my invention, and Fig. 6 is a view in front elevation with parts broken away or omitted, of a slightly modified form of my invention.

In my application Serial No. 779,972, filed 35 July 19, 1913, I have fully disclosed stopping mechanism for textile apparatus and particularly adapted for looms, wherein are employed heddle devices of the general character herein set forth. The heddle devices 40 herein represented are adapted to co-act with any suitable stopping instrumentalities, such for example as a cross rod, bar or tube, to be lifted upon warp fault and which may be connected in any suitable manner, as by the 45 means shown in said application, to the shipper mechanism. I therefore make reference to said companion application for a full disclosure of one type of means for operatively connecting the heddle devices to the shipper mechanism, but I desire it to be understood 50 that my present invention is not limited to the use of the connections there shown.

Looms have long been provided with warp

stop motions which have been placed in the harness so as to form a part thereof or have 55 been placed in the rear of the harness, but in almost all cases it has heretofore been necessary to rely upon the action of gravity; and therefore to use parts of substantial weight in the nature of drop bars or the 60 like. In all commercial stop motions for looms known to me employing heddle stops, the heddle has acted through gravity to initiate the stoppage of the loom. This has necessitated the use of metallic or like heddles inflexible or non-collapsible in the direction of its length, although highly flexible 65 laterally. In practice, the metallic drop heddles have given fair satisfaction upon certain kinds of fabrics, but upon certain 70 classes of warps, these heddles have been found to be impracticable, as they result in the roughening and chafing of the yarn and the breaking of its tender strands. In an attempt to overcome this objection, and particularly in the weaving of cloth involved in the use of finer and more delicate warps, the drops have been located behind the harness, and therefore in a position where they 75 do not receive that amount of vertical reciprocation incident to the shedding action of the warps, or in certain cases they have been so positioned that they receive no movement 80 due to the shedding action alone. The objections to this latter class of stop devices 85 are, however, serious, for there is involved a large complement or supply for each loom at least as many as the number of ends used. This involves, with many classes of drop devices, the drawing of the warp ends 90 through the drops as well as through the harness, thus largely increasing the labor incident to the preparation of the warp for the loom. While drop devices positioned back of the harness do less injury to the 95 warp ends in the weaving operation than do the metallic drop heddles, nevertheless the former class of drop devices does seriously injure certain classes of goods and especially silk goods. The so-called "cotton harness", 100 by which term I include harnesses made of textile material such, for example, as cotton or twine or material that is collapsible in the direction of its length, is universally acknowledged to be best adapted for use upon 105 fine work. I have succeeded in utilizing the

so-called "cotton harness" as a warp stop device, and thus I retain all the advantages of such class of harness and in addition avoid the necessity of drawing the warp 5 ends through a harness and also through drop devices. I thereby effect the shedding of the warp with the least possible chafing thereof, and at the same time there is necessitated no more labor in the drawing in of 10 the warp than in the ordinary type of looms having no warp stop motions.

Metallic drop devices are open to certain serious objections, such as the rusting and the electrifying thereof. The latter phenomenon, which is of frequent occurrence in loom practice, results in the holding of the drop of a faulty warp end in place, so that the warp fault is not indicated.

In the preferred embodiment of my invention, I employ stop devices, which are of the type of so-called "cotton harness", to which I have referred, and which do not rely or depend upon the action of gravity to effect the stoppage of the loom in the 25 event of warp fault. The stopping action is thus rendered more certain because no electrification of drops can occur, and because there is less crowding of parts. Moreover, in that embodiment of the invention 30 herein disclosed, I provide a positive initiation of the stopping action as contrasted with one which is initiated through the action of gravity. Furthermore in that embodiment of the invention herein disclosed, 35 the broken or faulty warp end is elevated above the plane of the warps or above the upper plane of the shed of the warps, instead of being depressed as heretofore, and thus the broken end may be readily seen and 40 more readily repaired.

Referring more particularly to the drawings, wherein I have typified my invention as applied to a loom, I have therein represented two heddle frames 1, 2 having upper 45 cross members 3, 4 and lower cross members 5, 6. I have herein represented my invention as applied to a loom having but a single pair of heddle frames, but it may be employed in a loom having any desired 50 number of heddle frames. The said heddle frames 1, 2 are reciprocated by any suitable shedding mechanism. For the sake of clearness, I have shown but a single heddle device 7, 8 in connection with each heddle frame. 55 Each heddle device is duplex in that it receives two warp ends and the number of heddles is proportional to the number of warp ends. The heddles are preferably composed of some suitable fibrous or textile material, such as cotton, though I desire it to be clearly understood that for the accomplishment of certain advantages and objects 60 of my invention, I may employ heddles formed partially or wholly of some suitable

metal or non-fibrous material, such for example as wire. I have represented each duplex heddle device as composed of a continuous twisted strand, piece or band of textile material, such as cotton, cord or twine, it being passed about the upper member 3 or 4 and the lower member 5 or 6 of its heddle frame in such a manner that it can travel longitudinally, that is, in the direction of its own length and in either direction. Each heddle device may be regarded, and particularly when viewed in side elevation as in Figs. 2, 3 and 4, as composed of two members lettered respectively A and B and C and D, although preferably each heddle device is continuous and uninterrupted. Each of the members A, B, C and D is provided with a suitable eye or warp receiving formation 9, 9', 9'', 9''', and through the several eyes pass the four warp ends respectively lettered a, b, c, d. Each 75 heddle device, being composed, in accordance with preferred embodiment of my invention, of a continuous strand of textile material, such, for example, as twine or cotton is of universal flexibility and is soft so as 80 not to act harshly upon the warp ends. To prevent stretching of the heddle devices upon warp stress, they are sized or otherwise suitably treated, and the eyes 9 may be 85 varnished.

Viewing each heddle device in front and also in side elevation, reference being made to Figs. 1 and 2, it will be observed that the ends of each heddle device are knotted together at 10 at or closely adjacent to the upper cross member 3 or 4 of the heddle frame. The knots of adjacent heddle devices on the same frame are preferably arranged in staggered relation, so as to permit the employment of a larger number of such devices 105 per inch without interference. From each knot 10 two strand portions 11, 12 extend down in parallelism to the point 13 where they are crossed or formed into a half knot constituting the upper limit of the warp 110 end receiving eye 9. The said strand portions are separated to form the eye 9, and are then brought together and recrossed at 14 to complete the eye, and are then continued downwardly as indicated at 15, 16 in 115 general parallel relation. Two strand portions 17, 18 indicated at the upper portion of Fig. 1, extend from the knot 10 about the cross member 3 or 4 and are continued downwardly in a manner similar to the strand portions just described to form the other heddle member. Each knot 10 also binds together the several strand portions 11, 12, 17 and 18. The strand portion 16 extending from the eye 9 passes under and about the lower cross member 5 or 6 of the heddle frame and is continued upward as the strand portion 19 to the eye 9' of the heddle 120 125

B. The other strand portion 15 extending downward from the eye 9, passes under the cross member 5 or 6 of the heddle frame and is continued upward as the strand portion 5 20 to the eye 9'. Thus I provide two loops passing under the cross member 5 or 6, one loop being composed of the strand portions 16, 19, being of sufficient length to fit rather closely about the cross member 5 or 6, and 10 the other loop being composed of the strand portions 15, 20, thus providing a considerably longer loop and which is intended to contact with the stopping instrumentality, herein represented as a tube 21 of sufficient 15 length to receive all the elongated loops of each heddle device. It will thus be observed that each heddle device has but a single knot, which is in its upper portion and preferably closely adjacent or in contact 20 with the cross member 3 or 4 of the heddle frame.

It will be observed that the warp end receiving eye or formation of each heddle member is elongated, it being preferably 25 varnished as previously stated for the reception of the warp end, and it will furthermore be observed that each eye is substantially centrally positioned with respect to the upper and lower cross members of its heddle 30 frame.

The length of each of the elongated loops composed of strands 15, 20 is such that during the shedding operation, as indicated in Fig. 3, the tube 21 is not lifted. When, 35 however, warp fault occurs, such as warp breakage and as indicated at *c* in Fig. 4, then the unbroken warp end *d* of the companion warp ends *c*, *d* received by the duplex device C, D, immediately imparts longitudinal movement to the heddle member D in the direction of the arrow in Fig. 4, because the said warp end *d* is in the shedding operation drawn from a true horizontal plane. The consequence of the downward 40 movement of the member D of the duplex heddle is the simultaneous upward movement of the member C thereof, carrying with it the broken or faulty end *c* into the elevated position shown in Fig. 4. Thus the movement of the member D of the duplex heddle is the simultaneous upward movement of the member C thereof, carrying with it the broken or faulty end *c* into the elevated position shown in Fig. 4. Thus the 45 broken or faulty warp end is lifted above the plane of the shed in which it occurs. This causes an abnormal pull or movement of the strand portion 15 of the elongated loop, and results in the lifting of the tube 21 from the dotted line position to the full line position indicated in Fig. 4, whereupon through suitable instrumentalities, such as shown in my co-pending application above referred to, the shipper mechanism is operated. 50

Inasmuch as in the disclosed embodiment of the invention, if there were not a positive connection between the tube 21 and the elongated loops, the members or strand portions

of such loops would merely move loosely about said tube when abnormal movement thereof occurs upon warp fault. I herein provide a strip 22 extending longitudinally of the tube 21 at its under side and secured by a series of screws 23 thereto, so as to 70 clamp each elongated loop to the said tube. Any other suitable connection may, however, be employed for the purpose, and in certain types of my invention, such a positive connection is not necessary. 75

I have thus far assumed that the warp end that is broken is one in the upper plane of the shed. It is evident that if the warp fault or breakage occurs when the broken or faulty warp end is in the lower plane of 80 the shed, the described movement of the heddle device upon its supporting members occurs when the heddle frame thereof is lifted in the shedding operation. In other words, if the warp end breaks when in the 85 lower plane of the shed, such warp end, as soon as it is moved into the upper plane of the shed, is immediately lifted above the plane of such shed, as indicated in Fig. 4.

It is not essential to my invention that the 90 duplex heddle thus be provided with two downwardly extending loop portions, although such construction is preferred. Within the scope of my invention, I may employ any suitable flexible connection extending from or forming a portion of the duplex heddle and attached in any suitable manner to the stopping instrumentality herein typified by the tube 21. A single 95 downwardly extending loop may be provided passing freely about the lower cross member 5 or 6 and any suitable flexible connection may be provided between the duplex heddle device and the said tube 21. In Fig. 5 the portion 15 is attached by strip 22' and 100 screws 23' to the tube 21, and the portion 20 is attached thereto by strips 22 and screws 23, said portions not forming a complete or continuous loop. Each portion 15 and 20 is unlooped. Neither is it essential to my 105 invention that the duplex heddle be provided with two upwardly extending loop portions, though such construction is herein illustrated and is preferred. In Fig. 6 I have, however, represented at A' a single 110 upwardly extending loop portion. Within the scope of my invention I may employ various connections between the eyes of each duplex heddle, to effect the shifting movement thereof in the event of warp fault. 115

It will be understood from the foregoing description that the stopping instrumentality is positive in its action and is not dependent upon the action of gravity. By avoiding the use of warp drops, I do away 125 with the necessity for drawing the warp ends through drop devices in addition to the heddles, and I am enabled to utilize the

so-called "cotton harnesses" which do not chafe or fray the warp ends.

Having thus described one illustrative embodiment of my invention, I desire it to be understood that although specific terms are employed, they are used in a generic and descriptive sense and not for purposes of limitation, the scope of the invention being set forth in the following claims.

10. Claims.

1. In a loom stopping instrumentality, a duplex heddle device of a single piece of material having two warp end receiving eyes or formations, two substantially equal length loops extending upwardly therefrom, a loop extending downwardly therefrom, a stopping instrumentality and a flexible connection from one at least of said eyes and attached to said stopping instrumentality.

20. 2. In a loom stopping instrumentality, a duplex heddle device of a single piece of material having two warp end receiving eyes or formations, a loop extending upwardly therefrom, a loop extending downwardly therefrom, a stopping instrumentality, and a flexible connection from one at least of said eyes and attached to said stopping instrumentality.

30. 3. In a loom stopping instrumentality, a duplex heddle device of a single piece of material having two warp end receiving eyes or formations, two substantially equal length loops extending upwardly therefrom and two unequal length loops extending downwardly therefrom.

40. 4. In a loom stopping instrumentality, a duplex heddle device of a single piece of material having two warp end receiving eyes or formations, said eyes being connected by four loops, two of which extend upwardly and are of substantially equal length and the other two of which extend downwardly and are of unequal length.

5. In a loom stopping instrumentality, a duplex heddle device having two warp end receiving eyes or formations, two substantially equal length loops extending upwardly therefrom and two unequal length loops extending downwardly therefrom.

50. 6. In a loom stopping instrumentality, a duplex heddle device having two warp end receiving eyes or formations, said eyes being connected by four loops, two of which extend upwardly and are of substantially equal length and the other two of which extend downwardly and are of unequal length.

60. 7. Loom stopping mechanism consisting of a heddle frame having upper and lower cross members, a transverse stop bar and a duplex heddle device having two warp end receiving eyes or formations from which extend two substantially equal length loops passing freely about the upper cross mem-

ber and two unequal length loops, one passing freely about the lower cross member and the other passing about said stop bar and operatively related thereto.

8. Loom stopping mechanism consisting of a heddle frame having upper and lower cross members, a transverse stop bar, and a duplex heddle device consisting of a single piece having two warp end receiving eyes or formations from which extend two substantially equal length loops passing freely about the upper cross member and two unequal length loops, one passing freely about the lower cross member and the other passing about said stop bar and operatively related thereto.

9. A loom stopping instrumentality consisting of a duplex heddle device of a single piece of textile material having two warp end receiving eyes or formations, two substantially equal length loops extending upwardly therefrom and two unequal length loops extending downwardly therefrom, and a stop device co-acting with one of said downwardly extending loops.

10. Loom stopping mechanism consisting of a heddle frame having upper and lower cross members, a transverse stop bar and a duplex heddle device having two warp end receiving eyes or formations from which extend two substantially equal length loops passing freely about the upper cross member and two unequal length loops, one passing freely about the lower cross member and the other about said stop bar, said latter loop being secured to said stop bar.

11. Loom stopping mechanism consisting of a heddle frame having upper and lower cross members, a transverse stop bar and a duplex heddle device having two warp end receiving eyes or formations from which extend two substantially equal length loops passing freely about the upper cross member and two unequal length loops, one passing freely about the lower cross member and the other about said stop bar, and a strip to secure said latter loop to said stop bar.

12. Loom stopping mechanism consisting of a heddle frame having upper and lower cross members, a stop device and a duplex heddle device having two warp end receiving eyes or formations from which extend two substantially equal length loops passing freely about the upper cross member and two unequal length loops, one passing freely about the lower cross member and the other engaging said stop device.

13. In a loom stopping instrumentality, a duplex heddle device of a single piece of textile material having two warp end receiving eyes, said piece having its ends knotted at the upper end of the device and having spaced half knots or crossings defining said eyes and also having two loops ex-

tending upward from said eyes and united at said knot, and two loops extending downward from said eyes and a stop motion instrumentality operatively associated with 5 one of said downwardly extending loops.

14. In a loom stopping instrumentality, a duplex heddle device of a single piece of textile material having two warp end receiving eyes, said piece having its ends knotted

10 at the upper end of the device and having spaced half knots or crossings defining said eyes, and also having two loops extending upward from said eyes, and two loops of unequal length extending downward from said

15 eyes.

15. In a loom stopping instrumentality, a duplex heddle device of a single piece of textile material having two warp end receiving eyes, said piece having its ends

20 united at the upper end of the device and having spaced half knots or crossings defining said eyes and also having two loops extending upward from said eyes and connected at said ends and two loops extending 25 downward from said eyes and a stop motion instrumentality operatively associated with one of said downwardly extending loops.

16. A loom stopping instrumentality consisting of a duplex heddle device of a single 30 piece of textile material having two warp end receiving eyes, said piece having its ends knotted at the upper end of the device and having spaced half knots or crossings defining said eyes, and also having two loops 35 extending upward from said eyes, and two loops of unequal length extending downward from said eyes, in combination with a stop motion actuating device within the longer of said downwardly extending loops.

40 17. In a loom stopping instrumentality, a duplex heddle device of a single piece having two warp end receiving eyes or formations, said piece having its ends knotted at the upper end of the device and having 45 spaced half knots or crossings defining said eyes and also having two loops extending upward from said eyes and united at said knotted ends and two loops extending downward from said eye and a stop motion instrumentality operatively associated with 50 one of said downwardly extending loops.

18. In a loom stopping instrumentality, a duplex heddle device, of a single piece of textile material having two warp receiving 55 eyes, said piece having spaced half knots or crossings defining said eyes and also having two loops extending upward from said eyes and united at said knot and two loops extending downwardly from said eyes and a 60 stop motion instrumentality operatively associated with one of said downwardly extending loops.

19. Loom stopping mechanism consisting of a heddle frame having upper and lower

cross members, a transverse stop bar and a 65 duplex heddle device having two warp end receiving eyes or formations from which extend two substantially equal length loops passing freely about the upper cross member, and two downward portions, one of 70 which is a loop passing freely about the lower cross member, and the other of which is attached to said stop bar.

20. Loom stopping mechanism consisting 75 of a heddle frame having upper and lower cross members, a stop member and a duplex heddle device having two warp end receiving eyes or formations from which extend two substantially equal length loops passing freely about the upper cross member and 80 two downward portions, one being a loop passing freely about the lower cross member and the other being attached to said stop member.

21. Loom stopping mechanism consisting 85 of a heddle frame having upper and lower cross members, a stop member and a duplex heddle device flexible in the direction of its length and having two warp end receiving eyes or formations from which extend two 90 substantially equal length loops passing freely about the upper cross member and two downward members, one passing freely about the lower cross member and the other being attached to said stop member. 95

22. A heddle having two openings for the reception of the warp ends, arranged to shift when released by one of the warp ends, an exterior member adapted to be connected to the shipper mechanism, means between 100 said heddle and said exterior member and attached to the latter to displace the latter to stop the loom upon the shifting of the heddle eyes.

23. In combination, a heddle having two 105 openings for the reception of warp ends, a heddle frame whereon said heddle is mounted for shifting movement when released by one of the warp ends, and a member exterior to said heddle frame and adapted to be connected to the shipper mechanism, said heddle having means between said heddle eyes and said exterior member and attached to the latter, to displace said exterior member, and thereby to stop the loom upon shifting 110 movement of said heddle. 115

24. In combination, a duplex heddle comprising two members having two openings for the reception of warp ends, a heddle frame whereon said duplex heddle is mounted for shifting movement when released by one of the warp ends, and a member exterior to but adjacent to said heddle frame and adapted to be connected to the shipper mechanism, said heddle having an extension attached to the exterior member, to displace the latter and thereby to stop the loom upon shifting movement of said heddle. 120 125

25. In combination, a heddle frame having upper and lower cross members, a duplex heddle having two openings for the reception of warp ends and mounted upon 5 said cross members for shifting movement when released by a faulty warp end, and a member exterior to said heddle frame and adapted to be connected to the shipper mechanism, said heddle having a flexible 10 portion attached to said exterior member,

thereby to move the latter and to stop the loom upon shifting movement of said heddle.

In testimony whereof, I have signed my name to this specification, in the presence of 15 two subscribing witnesses.

RANDOLPH CROMPTON.
